(57) **CLAIM**

The ornamental design for a garment, as shown and described.

DESCRIPTION

FIG. 1 is a front, left perspective view of a garment showing the present design, shown in a first in-use configuration; FIG. 2 is a front view thereof;

FIG. 3 is a first side view of the garment of FIG. 1 with a first sleeve of the garment in a raised position;

FIG. 4 is a second side view of the garment of FIG. 1 with a second sleeve of the garment in a raised position;

FIG. 5 is a first side view of the garment of FIG. 1 in a second in-use configuration;

FIG. 6 is a first side view of the garment of FIG. 1 in a third in-use configuration;

FIG. 7 is a first side view of the garment of FIG. 1 in a fourth in-use configuration;

FIG. 8 is a back view thereof;

FIG. 9 is a magnified view of the area indicated on FIG. 8; and,

FIG. 10 is a magnified view of the area indicated in FIG. 1. The broken lines with alternating long and short broken lines, immediately adjacent to the shaded area, represent unclaimed boundaries of the design. The unshaded regions represent unclaimed portions of the garment and form no part of the claimed design. The broken lines, which include even-length segments, that show the remainder of the garment or that are within the shaded area, are for environmental purposes only and form no part of the claimed design. The broken lines comprising an alternating pattern of two dashes separated by a dot are used to indicate the boundaries of a magnified view as shown in FIG. 9, and FIG. 10 and form no part of the claimed design. The contrast shading on the claimed portion is provided only to indicate the character and/or any contour or curvature of the surfaces. It does not indicate color, texture, markings that actually exist thereon, indicia, graphic representations, surface treatment, or any other ornamentation applied to the article.

1 Claim, 9 Drawing Sheets
